US00D472782S

(12) **United States Design Patent** (10) Patent No.: **US D472,782 S**
 Pusateri et al. (45) Date of Patent: ** Apr. 8, 2003

(54) **IMPACT WRENCH**

(75) Inventors: **Daniel S. Pusateri**, Grayslake, IL (US); **Joshua Beer**, Racine, WI (US); **Susan C. Melvin**, Zion, IL (US); **Raymond E. Kinsley**, Racine, WI (US); **James R. Brehm**, Racine, WI (US); **John A. Pierman**, Kenosha, WI (US)

(73) Assignee: **Snap-on Technologies, Inc.**,
Lincolnshire, IL (US)

(**) Term: **14 Years**

(21) Appl. No.: **29/158,353**

(22) Filed: **Apr. 2, 2002**

(51) LOC (7) Cl. **08-05**

(52) U.S. Cl. **D8/68**
